UNITED STATES PATENT OFFICE.

FRANÇOIS MARCEL, OF BROOKLYN, NEW YORK.

HAIR-WAVING IRON.

1,277,739.

Specification of Letters Patent. Patented Sept. 3, 1918.

Application filed December 18, 1916. Serial No. 137,533.

To all whom it may concern:

Be it known that I, FRANÇOIS MARCEL, a citizen of the United States, and a resident of the borough of Brooklyn, county of 5 Kings, and State of New York, have invented certain new and useful Improvements in Hair-Waving Irons, of which the following is a specification.

United States Patent No. 806,386 was issued to me (my name having since been changed by order of court) for a waving iron for producing what is known as the "Marcel" wave in women's hair and the present invention is of the same class, but 15 it is adapted to give results not heretofore attained.

One object of the present waving iron is to make it possible to produce a more lasting wave in the hair so that it will not require 20 waving as often as with other irons, and to produce a wave all parts of which will be more lasting.

Another object of my invention is to provide a waving iron which will produce a 25 more lasting wave with a given degree of heat so that, while the wave will last longer, it is not necessary to use the iron so hot as to injure or burn the hair.

Another object of my invention is to provide 30 an iron which will be very handy and which may be used by even unskilled persons to produce the desired waves.

Another and very important object of my invention is to provide an iron which will 35 create the most artistic and desirable wave in imitation of the natural hair wave. Heretofore, it has been difficult or impossible to produce a true imitation of the natural wave but with the present device the natural wave 40 may be imitated in every particular. It is not only possible to produce the lateral bends or curves but it is possible to produce the deep curves necessary to imitate the natural wave. It is also possible to produce effects 45 which could only be heretofore produced partially by the use of two separate irons having different dimensions.

The present iron is preferably, though not necessarily, heated electrically, and I have 50 shown it adapted to be so heated without intending to limit the invention to an electrically heated iron, except in so far as some of the claims herein particularly include the means for electrically heating the iron.

55 In the drawing forming part of this application,

Figure 1 is an elevation of my invention in the preferred form,

Fig. 2 is an elevation of the iron with the handles omitted, showing the parts in the 60 first position, or just as the iron is placed on the hair,

Fig. 3 is a similar elevation showing the iron turned over to produce the desired wave and showing the manner of disposing the 65 hair on the iron,

Fig. 4 is a partial sectional view of one of the waving members, showing the electrical heating unit therein,

Fig. 5 is an end elevation of Fig. 2,

Fig. 6 is an end view of Fig. 3,

Fig. 7 is a sectional view, taken on the line 7—7 of Fig. 2, and

Fig. 8 is a view corresponding to Fig. 7, showing a modified form having additional 75 advantages.

The iron comprises two main portions 1 and 2 having handles 3 and 4 respectively. The member 1 comprises a rounded portion or mandrel 5 which in the case of an electrically heated iron is made hollow, the space 6 forming a chamber to contain the electrical heating unit 7. The latter consists of resistance wire, a core, and suitable insulation and the same is not shown in detail as the 80 particular construction of this heating unit forms no part of the present invention. Units for this purpose are now on the market. The member 5 has a box 8 formed at its base and this box is closed by a removable cover 9 which carries the handle 3; and the unit 7 may be inserted and removed lengthwise of the member 5 by removing the cover 9. Wires 10, connected with the unit 7, may be connected in well known manner 85 with a source of current.

The members 1 and 2 are pivoted at 11 to one another and they are so constructed that when the handles are operated the members 1 and 2 will move the same as the jaws 100 of a pair of pliers.

The member 2 is concavo-convex in cross-section, the inner or convex side 12 being preferably formed on the arc of a circle.

There is a concavo-convex member 13 attached to or formed integral with the member 5 and it is so disposed that when the member 2 is closed against or nearly against the mandrel 5 one edge of the member 2 will lie between the outer edge of the member 110 13 and the mandrel 5. The member 13 extends outwardly from the mandrel 5, being

connected along one edge and separate at the other edge, so that a space or chamber 14 is formed and into which the hair may enter. Preferably, there is a filling member or enlargement 15 where the member 13 joins with the mandrel 5.

There is a guard 16 connected and movable with the member 2 the purpose of which is to prevent the hair from getting too far down 10 on the iron and entangling in the hinge, but this feature is not claimed, *per se*, in this case as it forms the subject matter of a co-pending case filed by me.

In the operation of waving the hair, after 15 the iron has become sufficiently heated, it will be placed on a lock of hair in the manner shown in Figs. 2 and 5; that is, the members 2, 5, will be caused to straddle the lock of hair and then the handles will be 20 forced toward each other so that the annular member 2 will press the hair against the mandrel. If the true "Marcel" wave is to be formed the hair will be directed diagonally in relation to the iron, as shown 25 in Fig. 2. In this first position, the hair will be clamped by the annular member 2 against the mandrel 5, forming a curve 17. It will be understood that the illustration of the hair in Figs. 5 and 6 is merely dia- 30 grammatic, as the hair will actually fill the space between the members 2 and 5 when they are closed. The hair beyond the loop 17 will turn over the edge 18 of the annular member 2 forming a short loop or curve 19, 35 reverse to the loop 17 and then it will pass around the free edge 20 of the member 13.

The iron will be placed on the hair as just described but it will be immediately turned over to the position shown in Figs. 40 3 and 6 and held that way until the heat has set the wave.

It will be noted that in the present iron the curve or loop in the hair at 19 is enclosed by the member 13, so that this portion 45 of the complete wave is subjected to sufficient heat to properly set the wave, whereas, heretofore, this portion of the wave has been improperly or insufficiently heated and as a result, the wave was not only not sufficiently pronounced but it was not lasting. In the present case the member 13 forms more or less of an inclosure about the member 5 and partly inclosing the edge of the annular member 2 and this also incloses the 55 portion of the hair which curves over the edge 18 of the annular member 2.

Another function of the member 13 is to provide for the formation of the desired shape of wave. It will be observed that 60 where the hair is pressed by the annular member 2 against the mandrel 5 it forms a curve or loop of lesser diameter but at 21 where it engages over the outer surface of the member 13 it forms a curve of greater 65 diameter, producing a "deeper" loop at this

portion of the complete wave. The smaller curve at 17 gradually merges into the larger curve 21 and this produces a wave of the desired shape and which others have heretofore attempted to produce by using separate irons of different diameters. The member 13, therefore, performs, in the embodiment of my invention herein shown, the double function of inclosing the curve 19 and imparting to it the required heat, and 75 of forming, together with the member 5, a wave of the desired formation.

The member 13 is here shown as being formed integral with the mandrel by rolling them up from sheet metal, and while this 80 construction is preferred because it makes it possible to stamp these parts, nevertheless I do not wish to exclude a construction in which these parts are otherwise constructed. I prefer to insert the filler 15 between the 85 member 13 and the mandrel so that the former will be firmer and to increase the conduction of heat through the member 13 to the hair.

When the operation just described has 90 been carried on long enough to set the curves in the hair the iron will be turned back and released and it will then be reengaged on the hair but beyond the point where it was first treated. In this second operation the 95 iron will be placed diagonally of the length of the hair but in the reverse direction to that shown in Fig. 2. In other words this diagonal tilting of the iron will be alternated at successive operations to produce 100 the desired effect. This is not imperative but it makes possible the exact imitation of a natural wave.

Heretofore, it has been difficult to force the hair down between the members 2 and 5 so that it was not held tightly between these members at the middle or any portion of the curve 17. This was due to the fact that the hair would be first impinged between the two edges of the annular member 110 2 and the mandrel 5 at opposite extremes of the loop 17 before the member 2 pressed the intermediate portion of this loop against the mandrel. As a result, the loop 17 was 115 not sufficiently affected by the heat to properly set it. In the construction shown in Fig. 8 I have arranged for what amounts to a three point contact on this loop by making the mandrel wedge shape in cross section on one side. The concave side of the 120 member 2 is preferably struck on the arc of a circle, but the mandrel 5 tapers from the point 22 outwardly, at both sides, to the points 23. With this conformation of the parts the hair will be carried down to the 125 bottom of the curve in the member 2 when the iron is closed thereon and there will be a bight not only between the side edges of the member 2 and the mandrel but there will be a bight between the point 22 and the 130

member 2, and sufficient heat will be conducted to the intermediate portion of the loop 17. This feature is not only important in an iron embodying the other features of my invention but it is susceptible of independent use and it will be separately claimed as well as in combination. This feature might be utilized, for instance, even if the iron consisted of only the members 2 and 5, without the member 13.

The device shown and described herein is not only simple in construction and easy to operate but it is a most efficient device for producing every effect desired.

Having described my invention, what I claim is:

1. A hair waving iron including mandrel and convex members hinged to swing in relation to each other and adapted to engage the hair between them to form a loop therein and a member carried by said mandrel member and arranged to overlap the edge of said convex member for the purpose set forth.

2. A hair waving iron including a mandrel member, and a concavo-convex member arranged so that its concave side will press the hair against said mandrel member, and a member projecting laterally from said mandrel member and adapted to overlap the edge of said concavo-convex member for the purpose set forth.

3. A hair waving iron including a mandrel member and a concavo-convex member movable in relation thereto and adapted to press the hair on the mandrel member, and a plate on said mandrel member, curving laterally therefrom and adapted to overlap an edge of said concavo-convex member for the purpose set forth.

4. A hair waving iron comprising a mandrel member, a concave member movable in relation thereto and adapted to press the hair on the mandrel member and a member

extending lengthwise along the mandrel member, said member being convex on its outer surface and having a free edge spaced from the mandrel member and arranged whereby when the said concave member is moved toward the mandrel member, its edge will carry the hair in between said free edge and said mandrel member.

5. A hair waving iron comprising a mandrel member having a projecting portion and a concave member adapted to press the hair on said mandrel member, the periphery of said mandrel and projecting portion being so shaped as to present a curve of lesser diameter where said concave member cooperates with the mandrel member and a curve of larger diameter on the side opposite thereto.

6. A hair waving iron comprising a mandrel member having a projecting member extending outwardly therefrom, and a concave member adapted to press the hair on said mandrel, the periphery of said mandrel member and said projecting member being shaped to present a curve of lesser diameter where said concave member cooperates with the mandrel member and a curve of larger diameter on the side opposite thereto, one edge of said concave member being adapted to press the hair into the space between the said projecting member and said mandrel member.

7. A hair waving iron comprising a mandrel one portion of the periphery of which is wedge shape or tapering in cross section and a grooved member adapted to press the hair against the mandrel and arranged whereby the wedge shaped portion of the mandrel will extend into the said grooved member for the purpose set forth.

Signed at the city, county and State of New York this 25th day of November, 1916.

FRANÇOIS MARCEL.
